United States Patent Office

Des. 175,657
Patented Sept. 20, 1955

175,657

AUTOMOBILE SIGNAL

William A. Uttz, Fort Worth, Tex.

Application April 4, 1955, Serial No. 35,360

Term of patent 7 years

(Cl. D72—1)

FIG. 1.

FIG. 3.

FIG. 2.

Fig. 1 is a front perspective view of an automobile signal, showing my new design.

Fig. 2 is a rear elevational view thereof; and

Fig. 3 is an end elevational view thereof.

The dominant features of my new design are shown in solid lines.

I claim:

The ornamental design for an automobile signal, substantially as shown and described.
